US0D1045836S

(12) **United States Design Patent** (10) **Patent No.:** **US D1,045,836 S**
(45) **Date of Patent:** **** Oct. 8, 2024**

(54) **STAND FOR AN AUDIO DEVICE**

(71) Applicant: **Sonos, Inc.**, Santa Barbara, CA (US)

(72) Inventors: **Vincent Wang**, East Palo Alto, CA (US); **Edward Mitchell**, Thousand Oaks, CA (US); **Eduardo Salazar**, Reseda, CA (US)

(73) Assignee: **SONOS, INC.**, Goleta, CA (US)

(**) Term: **15 Years**

(21) Appl. No.: **29/868,436**

(22) Filed: **Dec. 2, 2022**

(51) **LOC (14) Cl.** **14-01**

(52) **U.S. Cl.**

USPC **D14/224**

(58) **Field of Classification Search**

(57)

CLAIM

The ornamental design for a stand for an audio device, as shown and described.

DESCRIPTION

FIG. 1 is a front elevation view of a stand for an audio device, showing the new design.

FIG. 2 is rear elevation view thereof.

FIG. 3 is a top plan view thereof.

FIG. 4 is a bottom plan view thereof.

FIG. 5 is a right side view thereof.

FIG. 6 is a left side view thereof.

FIG. 7 is a first perspective view thereof; and,

FIG. 8 is a second perspective view thereof.

The features shown in broken lines form no part of the claimed design.

1 Claim, 7 Drawing Sheets
